H. R. WEBB, JR.

RATCHET WRENCH,

APPLICATION FILED APR. 12, 1917.

1,258,381.

Patented Mar. 5, 1918.

Henry Russell Webb Jr. Inventor

By his Attorney

W. B. Hutchinson,

UNITED STATES PATENT OFFICE.

HENRY RUSSELL WEBB, JR., OF EAST ORANGE, NEW JERSEY, ASSIGNOR OF ONE-HALF
TO LOUIS FRED GEORGE AND ONE-FOURTH TO MORRIS STEIGLER, BOTH OF NEWARK,
NEW JERSEY.

RATCHET-WRENCH.

1,258,381.

Specification of Letters Patent. Patented Mar. 5, 1918.

Application filed April 12, 1917. Serial No. 161,632.

To all whom it may concern:

Be it known that I, HENRY RUSSELL WEBB, Jr., a citizen of the United States, and a resident of East Orange, Essex county, New Jersey, have invented a new and useful Improvement in Ratchet-Wrenches, of which the following is a full, clear, and exact description.

My invention relates to improvements in ratchet wrenches, and the object of my invention is to produce an extremely simple, strong and easily operated wrench which can also be used for operating a die as well as a wrench jaw. More particularly my invention is intended to produce a ratchet wrench so simple that it will be inexpensive to make, so strong that it will be practically like a solid wrench, and so easily operated and adjusted that a jaw can be removed and another one with a different sized opening readily substituted when desired. My invention is also intended to produce a wrench having a split head, one member of which forms a part of the wrench handle, and the other member of which is hinged to the first member and closes against the handle to which it is easily fastened. My invention also comprises the construction of a jaw in which the ratchet teeth are formed on the exterior of the jaw and raised from the body of the jaw so as to turn in a channel of the wrench head. This makes the jaw simple to make, easy to adjust, and unlikely to receive injury in use.

Reference is to be had to the accompanying drawings forming a part of this specification, in which similar reference characters indicate corresponding parts in all the views.

Figure 1 is a broken side elevation partly in section of the wrench embodying my invention.

Fig. 2 is a side elevation with the wrench head thrown open.

Fig. 3 is a cross section on the line 3-3 of Fig. 1.

Fig. 4 is a detail of the jaw, and

Fig. 5 is an end view of the wrench.

The wrench is provided with a jaw member 10 which is of generally cylindrical shape, and has an opening 11 therethrough to receive a nut or the like. Obviously this jaw can be a die for cutting a thread, if desired. On the exterior of the jaw and extending around its circumference are ratchet

teeth 12. The jaw is carried by a split head 55 comprising members 13 and 14 which have an interior channel 15 which receives the teeth 12, thus supporting the wrench jaw 10 in place.

The two members 13 and 14 of the head 60 are hinged together at the wrench end as shown at 16, any suitable hinge being employed, and the member 13 merges into the handle or shank 17 which has preferably though not necessarily, a slot 18 at the end 65 to adapt it for use as a wrench at this end if desired. The head member 14 merges into the shank 19 which closes into a recess 20 in the side of the handle 17, and when closed completes the handle, the two parts 19 and 70 17 being fastened together by a thumb screw 21 or equivalent fastening.

The members 13 and 14 where they merge into the parts 17 and 19 are recessed as shown at 22, the recess opening out of the 75 channel 15, and in this recess and preferably in the member 13, is pivoted a pawl 23 to engage the teeth 12, the pawl being normally pressed into engagement by a flat spring 24 which lies in the recess 22, and the free end 80 of which rests against the back wall of the channel 15 in the member 14, thus securing the proper leverage to force the pawl into engagement with the teeth. It will be noticed that the end portions of the jaw 10 are 85 cylindrical and turn in the head members 13 and 14 which act as bearings for the jaw, while the teeth 12 being raised above the general surface of the jaw and turning in the channel 15, prevent the jaw from moving laterally. It will also be noticed that this construction leaves the side and end portions of the head flat and plain so that the wrench as a whole has no exterior projections that are likely to interfere with its 95 use. It will also be noticed that when the member 19 is closed into the recess 20, the handle is left smooth like a solid handle.

The wrench is used like an ordinary ratchet wrench, the jaw 10 being applied to 100 the nut and the wrench turned backward and forward as usual. When a different jaw is to be used, the wrench is opened by unscrewing the thumb screw 21, throwing open the head, removing the jaw 10 and substituting 105 another, after which the wrench can be closed and used.

It will be seen that the construction is of

the simplest nature, and that the wrench is very strong and easily operated and adjusted.

I claim:—

- 5 A ratchet wrench comprising a split head the members of which are hinged together at one end, provided with a cylindrical opening therethrough, and at one end merge into shank members adapted to meet 10 together to form a handle, one shank being shorter than the other and fitting in a corresponding recess in the opposed member,

the head having also an internal annular channel, a jaw member having cylindrical end portions turning in the opening of the 15 head and flush at the ends with the end portions of the head, ratchet teeth raised above the general surface of the jaw and running in the aforesaid channel, and a pawl pivoted in the head to engage the teeth.

HENRY RUSSELL WEBB, JR.
